Patented Nov. 21, 1916.

UNITED STATES PATENT OFFICE.

FRANK R. LINDSTROM, OF MILACA, MINNESOTA.

HARPOON HAY-FORK.

1,205,761.

Specification of Letters Patent. Patented Nov. 21, 1916.

Application filed February 8, 1915. Serial No. 6,820.

To all whom it may concern:

Be it known that I, FRANK R. LINDSTROM, a citizen of the United States, residing at Milaca, in the county of Millelacs, State of Minnesota, have invented certain new and useful Improvements in Harpoon Hay-Forks; and I do hereby declare the following to be a full, clear, and exact description of the invention, such as will enable others skilled in the art to which it appertains to make and use the same.

This invention relates to hay forks and more particularly to a harpoon fork of simple and improved construction.

15 An object of the invention resides in the provision of a harpoon fork in which are embodied novel means whereby the barb points thereof may be releasably secured in carrying position and automatically locked 20 upon movement to dumping position under the influence of a load on the fork.

With the above and other objects of similar nature in view, the invention consists in the construction, combination and arrangement of parts, set forth in and falling within the scope of the appended claims.

In the drawing, Figure 1 is a front elevation of a hay fork constructed in accordance with the invention. Fig. 2 is a top plan 30 view thereof. Fig. 3 is a vertical sectional view with the parts in carrying position, and Fig. 4 is a fragmentary perspective view of the upper portion of the fork with the handles in locked position.

35 Referring now more particularly to the drawing, the fork comprises the usual frame 10 including a cross head 11 and spaced parallel leg portions 12, resulting in a longitudinal slot 13 and terminating at their 40 free ends in sharpened points 14. Bridging the legs 12 adjacent their point of connection with the cross head 11 are spaced transverse bracing members 15, and pivoted at one end between said members are a pair of 45 operating handles 16, the upper ends of which project above and are slidably engaged as at 17 with the cross head and adapted for swinging movement relatively thereto.

50 Within the slot 13 adjacent the extremities of the legs 12 barb points 18 are pivoted, which points in one position extend longitudinally of the legs to permit the latter being readily inserted into a body of hay, 55 and in their other position extend at right angles to the legs and thus grasp the load

firmly so that it may be elevated to the desired height. Pivotedly engaged at their lower ends with the barbs 18 and at their upper ends with rocker links 19 disposed above the brace bars 15, are connecting arms 20, which arms serve to transmit motion to the barbs when it is desired to adjust same to grasp the load.

Additional links 21 are employed between the rocker links 19 and handles 16 so that by operating the latter the barbs 18 may be conveniently adjusted. To lock the handles 16 to the cross head 11 so that the barbs 18 will be in alinement with the legs 12, there 65 is mounted on the cross head, a spring plate 22, said plate being secured in position by means of eye bolts 23 and having its ends bent to provide resilient clips 24 adapted to releasably engage the related handle. It is 70 thus evident that the fork may be readily plunged into a body of hay without danger of displacing the barbs 18 and that, when it is desired to operate the latter to grasp the load, the handles are merely disengaged 75 from the clips and swung outwardly on their pivots and the barbs thus operated through the medium of the link and arm connection above described. It will be noted that in this position the upper ends of the arms 20 80 will be disposed inwardly of the pivot points of the rocker links 19 and any tendency for downward movement of the barbs under the influence of the load will thus be prevented.

There is further provided on the cross 90 head 11 the usual eye 25 for attachment with a hoisting cable by which the fork may be elevated. For releasing the barbs 18 when the fork has been elevated and moved to the desired position, the ends 26' of a trip line 95 26 are slidably engaged through the eye bolts 23 and connected at the upper ends of the handles 16, a slight jerk upon the line serving to carry the arms 20 beyond the pivots of the rocker links and allowing the 100 load to drop, the barbs 18 being thus moved to their positions in alinement with the legs 12 and the handles 16 automatically swung inwardly and locked beneath the clips 24.

What is claimed is:—

105 1. A harpoon fork including a frame, barb points pivoted to the frame, operating handles mounted on the frame, means operatively connecting said handles with the barbs to move and retain the latter in carrying position, trip means connected with said handles, resilient locking means secured to 110

the frame to automatically lock said handles to the latter upon movement of the barbs to dumping position under the influence of a load in the fork.

5 2. A harpoon fork including a frame, barbs pivoted to the frame, handles mounted on the frame and operatively connected with the barbs to move and retain the latter in carrying position, trip means connected with 10 said handles, and a resilient plate intermediately secured to the frame with its free

ends spaced therefrom, whereby to automatically lock the handles to the frame upon movement of said barbs to dumping position.

In testimony whereof, I affix my signature, in the presence of two witnesses.

FRANK R. LINDSTROM.

Witnesses:

C. E. ERICKSON,
JAMES NORCROSS.
